FRANK A. BECKLEY, OF EVANSTON, AND ARTHUR G. LARSON, OF CHICAGO, ILLINOIS;
SAID LARSON ASSIGNOR OF TWO ONE-HUNDREDTHS OF HIS EIGHT TO SAID
BECKLEY.

SUPPORT FOR CONCRETE FORMS.

Application filed May 6, 1926. Serial No. 107,209.

This invention relates to the means for supporting forms used in concrete work to maintain the shape of the concrete while it is setting. In concrete work, in ordinary practice, 5 timbers are employed to support the forms until the concrete is set and the upper ends of these timbers are generally braced by elements which form a T-head. If the lower floor or other base or support upon which the 10 timbers rest is uneven, imperfection in the work results and this is true if the concrete forms or the supports should shrink or from any other cause unevenness should develop. It is the primary object of the present invention 15 to provide means whereby the forms will be firmly supported and which may be readily adjusted so that any possible unevenness due to shrinkage will be overcome and eliminated. It is also an object of the invention to 20 provide a support which may be set up or taken down by a single workman and which, when not in use, may be easily stored in a small space. It is also an object of the invention to 25 provide a concrete form support which will be durable and may be produced at a cost which is not prohibitive. These stated objects, and other objects which will incidentally appear in the course of the following description, are attained in such a mechanism as is illustrated in the accompanying drawings, 30 and the invention resides in certain novel features which will be particularly pointed out in the appended claims.

In the drawings:

Figure 1 is a perspective view illustrating 35 the application of our invention;

Fig. 2 is an enlarged vertical section through a shore or prop constructed in accordance with the invention;

Fig. 3 is an enlarged view showing some of 40 the operating elements separated but in their proper relative positions;

Fig. 4 is a detail perspective view of the head which may be employed;

Fig. 5 is a detail section on the line 5—5 of 45 Fig. 2.

In Fig. 1, we have shown the invention arranged to support the form for a concrete beam as well as the form for a ceiling or floor, 50 and in both arrangements the support or prop comprises a column which is vertically extensible, and a head for direct engagement with a supporting bar, a brace generally connecting the props so as to brace them against lat-

eral spreading. The prop comprises a base 1 which is placed upon a lower floor or platform or other fixed support, and this base consists of a flat base having a cup or circular flange 2 on its upper side adapted to receive the lower end of a lower tube 3. The tube 3 fits closely within the flange 2 and is preferably secured therein by a pin or screw 4 inserted radially through the walls of the flange and the tube, as clearly shown in Fig. 2. The prop also comprises an upper tube 5 which is of the same diameter as the tube 3, and the upper end of this tube 5 fits closely within the annular flange 6 on the under side of a cap 7. In the upper end of the tube 3 is snugly fitted a bearing sleeve or collar 8 having an internally threaded bore and provided at its upper end with an annular shoulder or rim 9 which is adapted to rest upon the upper end edge of the tube 3, as clearly shown in Fig. 2. Pins or similar fastening devices, indicated at 10, are inserted through openings provided therefor in the tube and the bearing sleeve so that the sleeve will be held fixedly in the tube and will reinforce the upper end of the same. Normally resting upon the bearing sleeve 8 is a sleeve nut or turning head 11 which has an internally threaded bore of the same diameter as the bore of the sleeve 8 but has its external diameter slightly greater than the external diameter of the rim or head 9 of the bearing sleeve. The upper end of the sleeve nut or turning head 11 is greater in its external diameter than its lower end, as shown at 12, and at diametrically opposite points of the said sleeve nut are radially projecting lugs 13 which constitute handle members. These handle members are relatively short so that they are not apt to be broken when the device is disassembled and perhaps carelessly handled. Moreover, a short handle member offers slight obstruction to the passage of the workman in the neighborhood of the props or supports so that injuries to the workmen are not apt to occur. Should a longer leverage be desired, a pipe or tube may be easily fitted over either lug 13 in an obvious manner. The lower end of the upper tube 5 rests directly upon the upper end of the sleeve turning head or nut 11, and, to provide a wider bearing surface and also reinforce the lower end of the upper tube, a collar or ring 14 is fitted in the lower end of the tube and secured therein by

pins or the like, as indicated at 16. Engaged in and extending through the threaded bores of the bearing sleeve 8 and the sleeve nut 11 is a core 17, the lower portion of which is 5 threaded to mesh with the threads in the bores of the sleeve and the sleeve nut but the upper portion of which is smooth. A pin or the like 18 is inserted through the sleeve nut 11 so as to secure the nut in fixed relation to 10 the core and permit it to be utilized as a turning head. The upper portion of the core is of slightly less diameter than the reinforcing collar or ring 14 so that the parts may be easily assembled and possible wear upon the 15 core will be avoided. A guard sleeve or sheath 19 has its upper end fitted around the body of the sleeve nut or turning head 11 and secured thereto by a pin 20, as shown, the said guard sleeve being of appreciable length so 20 that it will depend around the lower tube 3 of the prop and thereby prevent the access of concrete or dirt to the lower tube. The greater external diameter of the upper end 12 of the turning head also aids in preventing the 25 access of concrete or dirt to the internal working elements, and it will be noted, particularly upon reference to Fig. 3, that said end 12 is beveled to turn aside any matter falling thereon so that the operative condition of the 30 device will be maintained at all times. The core is provided with an enlarged head 21 at its upper end which serves to prevent separation of the tube 5 and the core, after the parts have been once assembled, by engagement 35 with the inner upper end of the bracing collar or ring 14 in an obvious manner. This head 21 also maintains the vertical axial alignment of the upper tubular member with the lower tubular member and the core so as to 40 resist bending of said elements.

The cap 7 is a substantially U-shaped member comprising a base 22 from which the annular flange 6 depends and side flanges or walls 23 which rise from the edges of the base 45 or floor 22 in parallel relation. This cap may fit directly against a timber 24 which is utilized as the main support for planks 25 constituting the false work or form for a floor or ceiling, and openings 26 are provided in 50 the side walls 23 to permit a nail or similar fastening device to be driven into the timber 24 whereby to prevent relative endwise movement of the timber. It is frequently desirable to provide a more extended support for the 55 false work or concrete form and the invention includes means for furnishing such extended support. A head is fitted through and engaged with the cap 7 and said head comprises angle bars 27 arranged in parallel relation 60 and having their side flanges 28 cut away at their centers, as shown, the angle bars being connected in fixed spaced relation by blocks 29 at intermediate points of their length and by brackets 30 at their ends. The angle bars 65 are so spaced that their base members may extend through the cap 7 and rest upon the floor 22 thereof with the side walls 23 of the cap fitting in the cut-away portions of the side flanges 28, and the parts should be so disposed that the ends of the walls or flanges 23 70 abut the ends of the flanges 28 and the ends of the floor 22 abut the cross bars or blocks 29, endwise movement of the head through the cap being thereby prevented. The cap and head are intended to receive a bar 31 of 75 such dimensions as to fit closely between the flanges 28 and 23, and openings 32 are provided in the flanges 28 to permit nails or other fastening elements to be driven into the said bar 31 in like manner as such fastening devices are driven through the openings 26 in the side walls or flanges 23 of the cap. The brackets 30 are each provided with a slot or opening 33 in which is engaged the upper end of a diagonal brace 34, while clips or supporting brackets 35 are provided upon the tube 5 of the prop to receive the lower ends of the braces. The braces 34 may very conveniently be formed from T-bars having their flanges or stems 36 cut-away at their ends so as to 80 bear against the depending webs of the brackets 30 and the outstanding webs of the brackets 35, as shown clearly in Fig. 2 and as will be understood. When the stems 36 are cut-away, the ends of the head webs of the 85 braces or T-bars will, of course, be left projecting forming tongues 37 and 38. The tongues 37 are engaged through the slots 33 of the brackets 30 and are then bent in curvilinear form so that they constitute a hinged 90 connection between the respective braces and the ends of the head, while the tongues 38 are bent into angular relation to the main portion of the respective braces whereby they may depend vertically and be engaged 95 through slots 39 formed in the clips or brackets 35 when the head and the cap are brought into position over the upper end of the tube 5. These braces will then constitute firm supports for the ends of the head so that the 100 weight of the forms and the green concrete will be effectually carried and the strain exerted by such weight will be transmitted to the prop or shore in a manner which will 105 resist all tendency of the forms to assume 110 uneven positions during the shrinking which is incidental to the setting of the concrete.

At one or more points on each upper tube 5, we secure loops or clips 40 which are adapted to receive the ends of bracing boards 41 and are provided with openings 42 through which nails or the like may be driven to secure these bracing boards against withdrawal. These bracing boards are extended between two or more aligned props or shores 115 and thereby maintain the props in alignment and hold them against lateral displacement. The clips or loops 40 are arranged upon different radii of the respective props and also at different points in the height thereof so 120 125 130

that the boards may be readily placed in position without interference with each other. This arrangement also permits the use of a plurality of boards in connection with each 5 prop so that the prop may be braced in different directions.

In assembling the shore or prop, the bracing ring or collar 14 is secured in the lower end of the upper tube 5 and is intended to be retained 10 permanently therein while the bearing sleeve 8 is also intended to be retained permanently in the upper end of the lower tube 3. The base 1 may, of course, be permanently connected to the lower end of the tube 3, although 15 it may be sometimes found desirable, in order to save space in storage or transportation, to disassemble these elements. The turning head or sleeve nut 11 is permanently connected with the guard sleeve or sheath 19. When 20 the prop is to be set up for use, the core is inserted through the upper end of the upper tube 5 and the turning head or sleeve nut is brought into its proper position by engaging 25 the guard sleeve or sheath 19 over the bearing sleeve 8 and the upper end of the tube 3. The threaded end of the core may be then engaged in the bore of the turning head and the pin 18 inserted so as to secure these parts 30 together after the proper position of the core in the upper tube has been attained. The head and the cap are then brought into proper 35 relation and fitted on the upper end of the tube 5 with the tongues 38 engaged through the brackets 35, as will be understood. The props are then set up under the timbers 24 or the bars 31, as the case may be, and the 40 turning head is rotated to effect the proper adjustment and firm engagement of the head and cap with the timber or bar. When the 45 turning head 11 is rotated to the right, the core, of course, moves with the head but, owing to its threaded engagement with the bearing sleeve 8, it will ride upwardly therein, and the upper tube 5 will then, of course, move upwardly with the turning head and the 50 core and the timber 24 or the bar 31, as the case may be, will be held in direct contact with the described concrete form so as to rigidly support the same. When the forms 55 are to be wrecked, the head 11 is, of course, rotated to the left, thereby effecting a lowering movement of the upper tube 5 and the core. After the proper vertical adjustment 60 of all the props has been effected, the bracing boards 41 are secured in place and the device 65 will then need no further attention until the concrete has set and dismantling is to be effected.

It will be noted that the prop or shore of our 60 invention permits the concrete forms to be supported in a true level position notwithstanding any possible unevenness of the lower floor upon which the props rest, and any unevenness which may develop through shrinkage 65 may be readily compensated for by ad-

justing such props as may then be not sustaining the direct contact of the form elements which is desirable for efficient service. While endwise movement of the head through the cap 7 is prevented, the head is not attached 70 to the cap and may be easily lifted therefrom when the parts are to be disassembled for storage. After the head has been removed from the cap, the braces 34 may be readily 75 swung around so as to lie against the bottom or the top of the head and thus assume a very compact state which will permit the device to be placed within a very small space for storage or transportation. Likewise, the main tubes of the prop may be easily separated 80 and placed side by side or otherwise disposed to effect economy in storage space. The construction of our device is free of complications so that it may be set up and adjusted by one workman and may be produced 85 at a relatively low cost. The working elements are all enclosed so that seeping of concrete or access of dirt thereto is prevented and dripping water will be deflected so that it will not enter to and collect upon the threads 90 of the core or the parts engaged thereby and corrode the same. We prefer to use a coarse thread of square form inasmuch as such thread permits rapid adjustment of the core and the upper tube, and also serves as a lock 95 to hold the upper tube in its adjusted position. The bearing sleeve 8 provides a bearing surface more extended than would be had if the turning head rested directly on the upper end of the tube 3 and also tends to 100 simplicity in the construction and arrangement of parts whereby the rotary motion of the turning head is converted into endwise movement of the upper tube. When the device is set up for use, it occupies relatively 105 little floor space so that workmen and other persons may move freely around the scene of operations without being apt to cause some disarrangement of the forms or their supports and without incurring injury to themselves. When the prop is to be knocked down or disassembled, the core is withdrawn from 110 the lower tube by merely rotating the head 11 and there is no necessity for removing any other parts to effect withdrawal. If the pin 115 18 be then withdrawn, rotation of the head will cause the core to move endwise so as to be housed in the upper tube.

Having thus described the invention, we 120 claim:

1. Means for the purpose set forth comprising a prop, a cap carried by the upper end of the prop and having upstanding side walls, and a head extending through said cap and having its ends abutting the ends of 125 the side walls of the cap whereby to be held against endwise movement, and braces having their upper ends hingedly connected with the under side of the head and their lower ends removably held on the prop. 130

2. Means for the purpose set forth comprising a prop, a cap fitted on and carried by the upper end of the prop and including a floor and side flanges rising from the floor, 5 a head comprising angle members removably engaged through the cap to rest upon the floor of the same and having their side flanges cut-away between their ends whereby to abut the ends of the side flanges of the cap, connections between the said angle members at 10 the ends and at intermediate points thereof, the intermediate connections abutting the ends of the floor of the cap, and braces hinged at their upper ends to the ends of the angle members of the head and having their lower ends removably held on the prop.
3. Means for the purpose set forth comprising a prop, a U-shaped cap carried by the upper end of the prop, a head consisting of 20 angle bars having their lower webs resting on the floor of the cap and extending through the cap and their side webs abutting the ends of the cap, brackets connecting said angle members at the ends thereof and provided 25 with depending portions having slots there-through, slotted clips on the prop, and braces
- abutting the upper portions of the said slotted clips and the depending portions of the said brackets and provided at their lower ends with straight tongues fitting through the slots 30 of the clips and at their upper ends with curvilinear tongues engaged through the slots in the brackets.
4. Means for the purpose set forth comprising a prop, a cap carried by the upper end 35 of the prop, a head resting on the floor of the cap and extending through the cap, brackets at the ends of the head provided with depending portions having slots there-through, clips on the prop having outwardly 40 extending members provided with slots there-through, and braces abutting the upper surfaces of said clips and the depending portions of said brackets and provided at their lower ends with straight tongues fitting through the 45 slots of the clips and at their upper ends with curvilinear tongues engaged through the slots in the brackets.

In testimony whereof we affix our signatures.
